IGNITION DEVICE

James A. Rook and Clay H. Rook, Los Angeles,
Calif.

Application March 27, 1933, Serial No. 662,989

10 Claims. (Cl. 158—86)

This invention relates generally to hydrocarbon burners, more particularly to an ignition apparatus for the same.

One form of hydrocarbon burner generally employed in stoves or the like consists of combustion chambers formed by a plurality of cylindrical perforated shells or mantles that are mounted on a base having fuel distribution channels formed therein, together with wicks which serve to pre-
10 heat the mantles sufficiently to cause vaporization of the fuel.

In starting burners of this type it is necessary to light the wicks. This is usually done with a torch or the like. Lighting and subsequent han-
15 dling of the torch is not only troublesome, but it is necessary to remove the lids of the stove in order to reach the wicks. Various forms of ignition apparatus have heretofore been employed in lieu of the torch for the above stated purpose,
20 the most common of which produces a high tension electric spark adjacent the wicks.

Although such devices serve their intended purpose, they are not only expensive to install (due to the expensive auxiliary apparatus re-
25 quired) but light the wick at one or more points and only when the wick is in a proper relation thereto. As it requires some time for the wick to become entirely ignited, there is a tendency to give out oil fumes due to insufficient combustion
30 during this period. Also after this circle of fire is formed it is necessary to allow the same to burn long enough to heat the mantles sufficiently to cause vaporization, i. e. before admitting more fuel into the burner.

It is therefore the object of the present invention to produce an ignition apparatus which will eliminate the above stated objectionable features.

Another object is to provide an electric ignition apparatus which may be easily and quickly in-
40 stalled in a burner of the character referred to and which will instantly ignite the wick at all points.

A further object is to provide an ignition device for hydrocarbon burners that may be operated from usual 110 v. light current, or other A. C. or
45 D. C. circuits.

Other objects and advantages will be apparent from the following description, reference being had to the accompanying drawing, in which:

50 Fig. 1 is a vertical section taken through a stove and a hydrocarbon burner equipped with the ignition apparatus of the present invention.

Fig. 2 is a horizontal section taken on line 2—2 of Fig. 1.

55 Fig. 3 is a side elevation of the improved igni-

tion element applied to a burner tube shown in Figs. 1 and 2, parts being broken away and shown in section.

Fig. 4 is a top plan view with the mantle re-
moved.

Fig. 5 is a fragmentary vertical section taken on line 5—5 of Fig. 3.

Fig. 6 is a side elevation of a modified form of the invention.

Fig. 7 is a section taken on line 7—7 of Fig. 6. 10
Fig. 8 is another modified form.

Fig. 9 is a section taken on line 9—9 of Fig. 8. Referring by numerals to the accompanying drawing, more particularly to Figs. 1 and 2, 10
designates a stove or heater that is provided with 15 a conventional hydrocarbon burner 12.

Burner 12 consists of a plurality of concentri-
cally arranged cylindrical shells or tubes, in the
present instance four in number, indicated at
13, 14, 15 and 16, that are mounted on a cast 20
iron base 18.

The innermost tube and the space between
shells 14 and 15 are closed at the upper end there-
of as indicated at 19, while the open spaces be-
tween the tubes form combustion chambers des- 25
ignated at 20.

Formed on the base is a plurality of annular upstanding flanges 21 that support the tubes, there being a fuel channel 22 formed in the base below the combustion chambers and draft open- 30
ings 23 communicating with the space between the tubes. The hydrocarbon fuel is supplied through a pipe controlled by a valve (not shown) that communicates with the space 24 below the inner tube. Arranged in the fuel channels are 35
circular wicks 25 formed of non-combustible material such as asbestos, which when saturated with the liquid fuel and ignited serve to preheat the tubes sufficiently to vaporize the liquid fuel to produce combustion.

The present invention resides in the means for igniting the wicks and consists primarily of an annular member 28 formed of electrical insulating and non-combustible material, and an electrical resistance element encircling the same. In 45
the present instance the element is shown in the form of a resistance coil designated at 29.

Formed on the lower end of member 28 is an annular offset 30 that rests on a corresponding shoulder formed on the flange of the burner base, 50 and formed on the upper end of the member is a similar offset 31 that extends into and centers the combustion tube indicated at 32 thereon, as clearly shown in Fig. 3.

Resistance coil 29 rests in a groove 33 formed 55

in the peripheral face of member 28, the free end of which extends through openings 34 formed in a block 35 secured to or formed integrally with said member. The coil is engaged by a plurality 5 of hook shaped lugs 36 that hold the same in place on the member in case of breakage.

Formed in member 28 are a plurality of perforations 37 that serve to cause equal combustion.

Block 35 extends downwardly through the 10 draft opening 23 as shown in Fig. 1, and the terminals 38 of the coil are connected through heat insulated conductors 39 to the binding posts 40 of a conduit box 41 that carries a switch 42. Formed on the conduit box is a socket that receives the plug 43 of a flexible conduit that is 15 adapted to be connected to a lamp socket or other source of current.

The above described apparatus is particularly adapted to be installed in burners already constructed or in use, in which instance the combustion tubes to which the members 28 are applied should either be cut off or new ones of proper length supplied so that all the tubes will be flush at the upper ends.

25 Referring to Figs. 6 and 7, the member 50 is cast or otherwise permanently secured to the tube designated at 51 and is provided with a groove to receive the resistance coil 29', the terminals of which extend through openings formed in a 30 block 53. Formed in the member is a plurality of openings 55 that register with openings in the tube.

The above described form is adapted to be furnished with the burner or substituted for the 35 combustion tubes of a burner that is in use.

In the construction shown in Figs. 8 and 9, the member designated at 57 is secured to or formed 40 on a metal ring or band 56 that is adapted to be applied to the tube, and formed in the peripheral face of the member is a groove in which is mounted the resistance coil 29a. The terminals of the 45 coil extend through openings in a block 58, there being a recess 59 formed in the tube to permit passage of the block while applying the member to the tube. A plurality of aligned openings 60 are formed in the member and tube.

The above modified forms are adapted to be connected with the source of electric current in the same manner as that shown in Fig. 1.

50 In starting the burner, it is only necessary to turn on the switch 42 to energize the resistance coil, which (when it becomes hot) ignites the wick at all points, which in turn results in heating the tubes sufficiently to cause combustion, whereupon the switch may be turned off.

55 We claim:

1. A combustion tube burner having a base provided with a fuel channel, means to supply fuel to said channel, a combustion chamber above said fuel channel, a wick in said channel, and 60 means for igniting the wick and the fuel carried thereby at atmospheric temperature, said means comprising an electric resistance igniting element in said chamber positioned closely adjacent said wick and substantially coextensive therewith.

2. A combustion tube burner having a base provided with a fuel channel, means to supply fuel to said channel, a combustion chamber above said fuel channel, a wick in said channel, an insulating element in said combustion chamber, a resistance element carried by said insulating member and closely adjacent the plane of the upper end of said wick and substantially coextensive therewith.

extensive therewith for igniting the same at atmospheric temperature, and means for admitting air to said combustion chamber below said resistance element.

3. In a hydrocarbon burner including perforated tubes providing a combustion zone, a base having a fluid channel therein, a wick within the channel and extending into the combustion zone, an insulating member associated with said base and an electric resistance element carried by said insulating member adjacent said wick for igniting the same at atmospheric temperature, said insulating member being provided with perforations for the admission of air below said resistance element.

4. A combustion tube burner comprising a liquid fuel trough, a plurality of spaced, perforated combustion tubes extending upwardly therefrom forming a combustion zone, a wick in said fuel trough and extending to said combustion zone, an insulating member in the lower portion of said combustion zone, and an electric resistance element carried by said insulating member and positioned adjacent the upper end of said wick and substantially coextensive therewith for igniting the same and the fuel carried thereby at atmospheric temperature.

5. The construction as set forth in claim 4 and having means whereby air may be admitted to said combustion zone beneath said resistance element.

6. The construction as set forth in claim 4 wherein the insulating member is mounted on one of said combustion tubes.

7. The construction as set forth in claim 4 wherein the insulating member is mounted on said fuel trough and supports one of said combustion tubes.

8. A combustion tube burner having a base provided with a fuel channel, means to supply fuel to said channel, a combustion chamber above said fuel channel, a wick in said channel, insulating means in said combustion chamber, a resistance element carried by said insulating means and closely adjacent the plane of the upper end of said wick and substantially coextensive therewith for igniting the same at atmospheric temperature, and means for admitting air to said combustion chamber below said resistance element.

9. A combustion tube burner comprising a liquid fuel trough, a plurality of spaced, perforated combustion tubes extending upwardly therefrom and forming a combustion zone, a wick in said fuel trough and extending to said combustion zone, insulating means in the lower portion of said combustion zone, and an electric resistance element carried by said insulating means and positioned adjacent the upper end of said wick and substantially coextensive therewith for igniting the same and the fuel carried thereby at atmospheric temperature.

10. A combustion tube burner having a base provided with a fuel channel, means to supply fuel to said channel, a combustion chamber above said fuel channel, a wick in said channel and means for igniting the fuel, said means comprising an electric resistance igniting element in said chamber positioned above said wick to be directly in the range of active combustion and substantially coextensive therewith.
